COMBINED LEAF HOLDER AND BOOKMARK

Otto L. Hermann, St. Louis, Mo., assignor to
 Buxton & Skinner Printing & Stationery
 Company, St. Louis, Mo.

Application January 26, 1938, Serial No. 136,973

8 Claims. (Cl. 281—42)

This invention has for its general object to provide a novel combined bookmark and leaf holder which shall be characterized by simplicity of construction and consequent economy in manufacture, which may be readily applied in position on the book and as readily removed for application to a new book; and which shall be compact in design and of light construction, so that in use on the character of record books for which it is particularly designed, the book may be carried about, or placed in the pocket, without any inconvenience being caused by the presence of my device on the book.

My improved device is intended for use particularly on blank record books of the type used by employees of gas, water and electric light companies in recording the readings of meters at the houses, factories, shops, etc., visited for the purpose, although the invention is not limited in application to this particular type of book. Such books are usually of the loose-leaf variety, are relatively long, narrow and thick, and are hinged at one end. The device is placed in position on the front cover of the book, and presents a spring-pressed roller of the width of the cover, and preferably having a surface of rubber, which is yieldably held against the inside of the cover and under which each leaf as used may be easily inserted to be held against the cover, or against a leaf, or leaves, previously inserted under the roller; or any number of leaves may be simultaneously inserted under the roller and clamped thereby to the cover, according to the place in the book which it is desired to mark.

My improved device comprises a body portion in the form of a slide member, which is adapted to receive and be slidably mounted on the front cover of the book and which is provided along the upper edge portion of its rear side with a cylindrical housing, a coil spring mounted in and secured at one end to said housing, a bail having a cross-bar extending through and pivotally mounted in the ends of the housing, and controlled by said spring, the other end of which is secured to the cross-bar, and a roller mounted for rotation at the outer ends of the arms of said bail.

In the accompanying drawing—

Fig. 1 is a plan view of a book with my device in position on the cover thereof;

Fig. 2 is an edge view, looking toward the left of Fig. 1;

Fig. 3 is a plan view, with the book shown in Fig. 1 opened, and showing the leaves held in position against the inside of the front cover by the spring-pressed roller;

Fig. 4 is an enlarged plan view of the device, a part of the roller being shown in section;

Fig. 5 is a transverse section, taken on the line 5—5 of Fig. 4 and viewed in the direction of the arrows;

Fig. 6 is an end view of the device; and

Fig. 7 is a cross-section, taken on the line 7—7 of Fig. 4 and viewed in the direction of the arrows.

The body of the device which, as stated, is adapted to be mounted on the front cover of the book, comprises two parallel plates 1, 2, respectively, providing between them a space 3, through which the cover 4 of the book is adapted to be inserted, the body being thus slidably adjustable on the cover to any desired position, usually about midway of the ends. The outer plate 2 is provided along one edge with a cylindrical housing 5 which incloses a coil spring 6, one end of which is secured to the housing and the other end to a cross-bar 7 extending through, and rotatably mounted in the ends 8 of the housing, said shaft, or cross-bar, being bent at right-angles to itself at each end to provide parallel, curved arms 9, in the outer end of which is mounted a spindle 10, on which is rotatably mounted a rubber roller 11, longitudinally corrugated as indicated at 12. The outer plate 2 is also provided at opposite ends with right-angle flanges, or heads, 13, each of which is provided at its lower end with a stop 14, against which the arms 9 normally bear under the action of spring 6.

In use, the device is placed in position on the book by inserting the front cover in the space 3 and sliding the device to the desired position on the cover, the device then having the position on the book shown in Fig. 1. When the book is opened, as shown in Fig. 3, and the meter reading, or other record, made on a page 15 thereof, the latter may be readily inserted under roller 11, which freely rotates on its spindle. When the book is closed, the roller rolls over the retained page, or pages, without liability of doubling or creasing them, and the same applies when the book is opened. The book may be opened by merely raising the cover, the roller 11, by holding the used leaves against the cover by pressure of spring 5, always insuring that the book will be opened at the place divided off by the roller. The latter thus acts in the nature of a bookmark.

It will be obvious that the device can be made of a width to suit any given size of book, and therefore that it can be made of a width to enable it to be placed on a book opening at the side, as in the case of an ordinary library book.

What I claim as new is:

1. A combined leaf holder and bookmark comprising a body portion provided with a rectangular space for slidably receiving the cover of a book, a spring-controlled bail carried by the body portion, and a roller mounted on said bail, for extending across the inside of the cover and to be yieldingly held in engagement with the same by the bail.
2. A combined leaf holder and bookmark comprising a body portion provided with a rectangular space for slidably receiving the cover of a book, a spring-controlled bail pivotally mounted on the body portion, and a roller mounted on said bail, for extending across the inside of the cover and to be yieldingly held in engagement with the same by the bail.
3. A combined leaf holder and bookmark comprising a body portion providing a rectangular space adapting the body portion to be slidably and removably mounted on the cover of a book, a spring-controlled bail pivotally mounted on the body portion, and a roller carried by said bail, for extending across the inside of the cover and to be yieldingly held in engagement with the same by the bail.
4. A combined leaf holder and bookmark comprising a body portion providing a rectangular space adapting the body portion to be slidably and removably mounted on the cover of a book, a spring-controlled bail pivotally mounted on the body portion, and a rubber roller carried by said bail, for extending across the inside of the cover and to be yieldingly held in engagement with the same by the bail.
5. A combined leaf holder and bookmark comprising a body portion providing a rectangular space adapting the body portion to be slidably and removably mounted on the cover of a book, a spring-controlled bail pivotally mounted on the body portion, and a longitudinally corrugated rubber roller carried by said bail, for extending across the inside of the cover and to be yieldingly held in engagement with the same by the bail.
6. A combined leaf holder and bookmark comprising a body portion providing a rectangular space adapting the body portion to be slidably and removably mounted on the cover of a book and having a transverse housing, a bail having a cross-bar extending through and pivotally mounted in the ends of said housing and provided with downwardly-extending, parallel arms, a coil spring surrounding said cross-bar and secured at one end thereto and at its other end to the housing, and a roller mounted at the outer ends of said arms, for extending across the inside of the cover and to be yieldingly held in engagement with the same by said bail.
7. A combined leaf holder and bookmark comprising a body portion providing a rectangular space adapting the body portion to be slidably and removably mounted on the cover of a book and having a transverse housing, a bail having a cross-bar extending through and pivotally mounted in the ends of said housing and provided with downwardly-extending, parallel curved arms, a coil spring surrounding said cross-bar and secured at one end thereto and at its other end to the housing, and a roller mounted at the outer end of said arms, for extending across the inside of the cover and to be yieldingly held in engagement with the same by said bail.
8. A combined leaf holder and bookmark comprising a body portion provided with a rectangular opening extending through the same from top to bottom for slidably receiving the cover of a book and provided at the top of its rear side with a housing and with end members affording stops, a bail having a cross-bar extending through and pivotally mounted in the ends of said housing and provided with downwardly-extending, parallel arms normally resting against said stops, a coil spring surrounding said cross-bar and secured at one end thereto and at its other end to the housing, and a roller mounted at the outer ends of said arms, for extending across the inside of the cover and to be yieldingly held in engagement with the same by said bail.

OTTO L. HERMANN.
